United States Patent Office

Des. 189,120
Patented Nov. 1, 1960

189,120

HAT

Macario Cuellar, Jr., 171 Howell St., Dallas, Tex.

Filed July 27, 1959, Ser. No. 56,957

Term of patent 14 years

(Cl. D3—13)

I claim:

The ornamental design for a hat, substantially as shown.
